[57] ABSTRACT

A lock primarily useful in producing gang forms, employs a slotted-cam in a pivoted lock plate to engage the head of a form-tie. The lock plate carries an integral rugged, bent over extension or strike arm which serves to cover the head of a form-tie and to receive heavy blows during either the closing or opening of the lock.

LOCK FOR FORM-TIES

SUMMARY OF THE INVENTION

Gang forms for use in the repeated placement of poured-in-place concrete have been widely adopted and used in the construction industry in the production of high-rise shear walls, elevator shafts and the like. A gang form is usually a large modular panel formed of several 4 x 8 sheets of plywood joined into a unit by numerous walers and peripheral frame members on the outer face. Numerous holes according to a predetermined pattern are made through the plywood and walers to receive form-ties which spread apart and tie together an opposed pair of such forms. For repeated use of such panels it is common practice to mount at the outer end of each of said holes a form-tie lock mechanism which engages the end of a form-tie. Such mechanism usually includes a pivoted lock plate having an arcuate cam slot which engages the shank and disposes itself under the head of the form-tie. Means is also included to cover the head of the form-tie to prevent its movement outward and the collapse together of the opposed form panels. Such means have usually comprised an added on metal bridge-like member straddling the head of the form-tie. Such members, standing out as they do, are often struck heavy blows both during assembly and disassembly by the workmen. As a result they rapidly become deformed or irreparably damaged and must be replaced. Further they provide tunnel-like openings in which concrete can become lodged to harden and clog the mechanism and, thus, interfere with disassembly. It has therefore been a primary object of this invention to provide for form ties a lock mechanism which is rugged, not easily clogged, easy to install and use and reuse in assembly and disassembly of gang forms, and which by reason of its design practically compels the workmen to strike the lock plate at the most effective and least damaging points.

DESCRIPTION OF THE DRAWINGS

FIG. 1 is a perspective view of a lock plate for form-ties according to this invention;

FIGS. 2, 3 and 4 are views serially illustrating the locking action of the lock plate;

FIG. 5 is a cross-section on line 5-5 of FIG. 4;

FIG. 6 is a cross-section on line 6-6 of FIG. 4; and

FIG. 7 is a cross-section on line 7-7 of FIG. 6.

DETAILED DESCRIPTION

The lock of this invention is usually attached to waler 10 that is secured to the face of a form panel 12, commonly a plywood sheet. Prior to the attachment of the lock plate the panel 12 and waler 10 are drilled to provide a hole 14 in which a form-tie 16 is disposed when two such panels are being assembled in preparation to casting concrete to produce a wall. A form-tie 16 usually comprises a shank 18, having snap or break point 20, forming cone 22, plug 24, and head 26 at each end. The normal function of a double-ended form-tie 16 is to tie together and at the same time space apart an opposed pair of panels 12, in this case in common practice of gang forming.

The lock of this invention comprises the base plate 30 supporting lock plate 32, attached thereto by pivot pin 34. Plate 30 has an aperture 36 which is aligned

with hole 14 when the lock is attached to waler 10 as by nails 38.

Lock plate 32 has a curved, open-ended camming slot 40 which is concentric of the axis of pivot pin 34. The edges of slot 40 rise from plate 32 and function as cam means increasing in height as they move under head 26 of the form-tie 16. This is probably best seen in FIG. 5.

Plate 32 at the end opposite the pivot 34 has an integral extension 44 which curves at 46 out from the plane of plate 32 and folds thereover to be disposed in cantilever fashion in spaced relation over the gullet or inner end of slot 40. In the preferred forms shown in the drawings, extension or strike arm 44 is shaped to lie diagonally over plate 32 and to terminate in a substantially acutely angled horn 48.

Plate 30 and lock plate 32 and its extension or strike arm 44, are formed to be very rugged and strong, it being preferable to use high quality steel about 1/4 inch thick. This is to resist the beating such devices suffer during the erection and disassembly of concrete forms. Ordinarily during assembly the carpenters or other workmen must drive the locking slot into the tight or gripping position by striking blows with their hammers. The bend 50 is provided for just this purpose. It is strong and openly exposed to be easily accessible. Conversely during disassembly, the horn 48 is ideally located and related to plate 32 so that a hammer blow is easily and accurately applied at the point where it will do the most good to force plate 32 to pivot and draw the cam slot 40 out from under tie head 26. Note that blows of a hammer on strike arm 44 to close the lock applied to bend 50, or to open it as on horn 48, are both normal to or across the width of extension 44, in other words across its greatest strength largely produced by its thickness and the strong bend 50.

Extension 44 overhangs the gullet of slot 40. When a form-tie head 26 is disposed thereunder the form-tie 40 cannot further extend through the form or base plate. Ordinarily at the time a form is being assembled there is little or no outward pressure tending to spread the panels. The overhang of head 26 by extension 44 prevents them from collapsing together.

The cantilever arrangement of extension 44 serves a very useful purpose. Occasionally when concrete is being placed in the forms some is spilled or some may escape from the forms via the form-tie holes. In either event it may become lodged in slot 40, or adjacent head 26 under extension 44 and there harden. The space under extension 44 being open and accessible from all but one direction makes it easy for a disassembly workman to insert a prod or bar and knock the mass loose.

It will be seen from the foregoing description that the objects of this invention have been accomplished in that an easy to construct, simple to use lock for form-ties has been provided; that the same is rugged and durable for use under severe conditions; and that a heretofore difficult problem has been overcome. Naturally modifications in size and shape will occur to those skilled in the pertinent art. All such, as by a reasonably liberal application of the doctrine of equivalents, as fall within the scope and spirit of the following claims is intended to be covered by this patent.

What is claimed is:

1. In a lock for headed form-ties wherein:

a base plate is attached externally on a form panel and has an aperture to receive and pass outward the headed end of a form-tie; and
 a lock plate is pivotally mounted on said base plate to swing about an axis offset from said aperture, and said lock plate has an open ended camming slot concentric of said axis and registered with said aperture, said slot being of a size to embrace the shank of and to be disposed under the head of a form-tie; the improvement, comprising:
 5 said lock plate opposite its pivotal axis having an integral extension reversely curved out of the plane of said plate into cantilevered overlying relation to

the closed end of said slot; said cantilevered integral extension providing impact-receiving surfaces oriented to transmit the force of locking and unlocking impacts to said lock plate remote from its pivotal axis and substantially tangential to the curvature of said slot in the proximity of its closed end.

2. The structure of claim 1 in which said extension terminates in a horn.

10 3. The structure of claim 1 in which said extension is disposed diagonally over said lock plate and terminates in an acutely angled horn.
